JOHN T. COLLINS Inventor

By Richard B. Dyer

Attorney

UNITED STATES PATENT OFFICE.

JOHN T. COLLINS, OF KOKOMO, INDIANA.

HEATER.

Application filed December 31, 1919. Serial No. 348,522.

To all whom it may concern:

Be it known that I, JOHN T. COLLINS, a citizen of the United States, residing at Kokomo, in the county of Howard and State of Indiana, have invented certain new and useful Improvements in a Heater, of which the following is a specification.

This invention relates to new and useful improvements in heaters, the primary object 10 of the invention being to provide an attachment for a furnace whereby the maximum amount of heat may be derived therefrom.

Another important object of the invention is to provide a device of the above nature including means whereby the fire around the walls of the furnace is compelled to burn more violently than the fire in the center of the furnace thereby heating the walls of the furnace to heat air surrounding the same.

20 My invention also consists in the construction, arrangement and combination of parts to be more fully set forth in the following description and accompanying drawings, and pointed out in the appended claims.

25 In the accompanying drawings forming a part of the description and wherein like numerals are employed to designate like parts throughout the several views,

Figure 1 is a vertical section taken through the heater, the casing therefor being shown in dotted lines,

Figure 2 is a horizontal section taken on the line 2—2 of Figure 1,

Figure 3 is a vertical section through the radiator taken on the line 3—3 of Fig. 2,

Figure 4 is a vertical section of the radiator taken on the line 4—4 of Fig. 2,

Figure 5 is a transverse section of the radiator taken adjacent the bottom thereof,

Figure 6 is a bottom plan of my center fuel plate,

Figure 7 is a transverse section of the same taken on the line 7—7 of Fig. 6, and

Figure 8 is a transverse section of my improved center fuel plate as applied to a revolving grate.

In the drawings, wherein for the purpose of illustration is shown a preferred embodiment of my invention, the numeral 9 designates a furnace of any desired construction having located therein the usual fire pot 10 under which is positioned any type of grate 11, preferably of the rocking type as shown in Fig. 1 or of the revolving type as illustrated in Fig. 8.

What I term as my center fuel plate is designated by the numeral 12 and assumes the form of a circular plate 12 which may be either positioned centrally of the grate and slightly thereabove as most clearly shown in Fig. 1 of the drawings or may rest on the grate. This plate is provided with an annular, depending flange equipped with radial passages therethrough to receive a portion of legs 13 as shown in Fig. 6, each of which is slotted to receive therein the shank of a bolt 14 whereby the legs are adjustably associated with the under side of the fuel plate. Preferably, these supporting legs radiate from the fuel plate, and the circumferential edge of the plate is under cut whereas the plate may receive the maximum amount of coal or fire.

When a fire has been made in the furnace, it will be seen that the fire will burn intensely around the edge of the center fuel plate, and the fire will eventually burn its way up over the plate. Consequently the fire may be managed so that the burning mass is concentrated around the edge of the plate and whereby the walls of the fire pot and furnace may be heated to a maximum point whereby the furnace will give out the greatest amount of heat. However, should the fire burn up over the center fuel plate, the live or hot coals may be removed therefrom with a poker or any other suitable implement so that the hot fire will be maintained around the edge of the plate and adjacent the walls of the furnace. Then, fresh coal or fuel is shoveled directly upon the center fuel plate to be consumed in the manner above set forth.

This center fuel plate when associated with forming a part of a revolving grate 15 as shown in Fig. 8 of the drawings, assumes the form of a circular plate 12', which is equipped with a centrally disposed depending projection 16. This projection 16 is mounted in an axially disposed socket carried by the supporting spider 17, the arms of which are secured to the furnace or fire pot in any suitable manner. This socket supporting bracket is equipped with a plurality of ball bearings 18 to engage the under face of the plate 12' to permit of the revolving grate to be moved more readily when it is shaken or revolved.

The improved radiator which is arranged in close proximity to the furnace 9, consists of a vertically disposed cylindrical casing

285,580
 19 supported well above the floor by the medium of supporting legs 20. Products of combustion are directed from the furnace 9 into the radiator through the medium of 5 suitable conduits, in the present instance consisting of a pair of horizontally arranged pipes 21, which communicate at one end with the radiator approximately intermediate its height, while the other ends of the pipes 10 communicate with the interior of the furnace a suitable distance above the fire pot.

A hot air pipe 22 is arranged centrally of the radiator casing 19 and extends vertically therethrough, the lower end of the 15 pipe being flush with the bottom of the radiator casing and having its edges secured to the edges of an opening provided in the bottom of the casing 19. The upper end of the hot air pipe 22 extends through an 20 opening in the top of the casing, a substantial distance therebeyond or may be secured to the top of the casing in the same manner as the lower end of the pipe. The hot air from the pipe 22 mingles with the air in the 25 casing 25 and rises into the hot air outlet pipe 24 to be conveyed to various rooms. As most clearly shown in Fig. 2 of the drawings, the casing 25, is provided upon opposite sides with extensions 26 arranged 30 adjacent the lower edge of the casing and provided with air inlet openings 27, whereby cool air may be admitted to the lower end of the casing. A plurality of radiating partitions are provided within the radiator, 35 and one longitudinal edge of each is secured to the inner surface of the radiator side walls, while the other longitudinal edge of each partition is secured in any suitable manner to the relative outer surface of the 40 hot air pipe 22. These partitions are provided solely for the purpose of retarding the products of combustion delivered from the furnace around the hot air pipe 22, so that cool air passing up therethrough will 45 become heated to a high degree. One of these partitions 28, which I term a dividing partition, extends from the top to the bottom of the radiator casing and is of course, disposed vertically between the two conduit 50 pipes 21 which lead from the furnace, whereby air from one conduit is caused to pass around one side of the radiator, while the air from the other conduit is caused to pass around the opposite side of the radiator. 55 A pair of diametrically disposed partitions 29 are also arranged within the radiator and at right angles to the dividing partition. These partitions 29 extend from the top of the radiator, to a point spaced from the bottom thereof, whereby products of combustion 60 are caused to travel to the lower end of the radiator after being delivered therein to from the conducting pipes 21. A second pair of partitions 30 are also provided within the radiator and radiate from the center

thereof. These two partitions 30 are spaced apart and are arranged upon the side of the radiator opposite to the dividing partition 28. As clearly shown in Fig. 1, these partitions extend vertically from the bottom of the radiator, to a point spaced from the top thereof, whereby the products of combustion rising from under the partitions 29 is caused to travel to the top of the radiator, thereby delaying the progress of the hot air as much as possible so that the cool air passing up through the hot air pipe 22 will obtain the maximum amount of heat. 75

In order to provide a draft, and in order that the products of combustion will be caused to travel in the preferred course, a pipe 31 is led from the lower end of the radiator, through the side of the casing 25 and terminates a short distance from the outer side of the casing 25. This end of the pipe is closed by a door 32 pivotally connected to the end of the pipe 31 whereby the door may be opened and a suitable cleaning implement inserted to gain access to the interior of the radiator for cleaning purposes. A pipe 33 rises from the pipe 31 to conduct smoke to a chimney from the radiator. It is, of course, to be understood that I may employ as many hot air pipes 22 through the radiator, as may be necessary to meet varying conditions, and that the pipes may be of any desired shape, and that other partitions, and other arrangements of partitions may be provided to accomplish the functions above set forth. 90

As set forth previously, the center fuel plate 12, will cause the fire in the furnace to burn most intensely around the walls of the furnace, and consequently greater amount of heat will be caused to radiate from the walls of the furnace. This heated air will of course travel upwardly within the casing 25, to the heat conducting pipe 24. Further, a great amount of hot air will pass through the conducting pipes 21 as will all smoke, and what flames may leap from the fire. The products of combustion which are delivered into the radiator, will be caused by the dividing partition 28 to travel around each side of the hot air pipe 22 through which passes cool air to become heated. The products of combustion after being delivered into the radiator will be caused to move downwardly by the partitions 29 and pass thereunder, after which the products of combustion will be caused by the partitions 30 to move or travel upwardly of the radiator, whereby it may escape over the top of the partitions 30. By this time it is estimated that quite a bit of heat will be derived from the products of combustion delivered from the furnace and due to the draft caused by the pipe 33, the smoke will be caused to travel downwardly of the radiator to escape into the outlet pipe 31 and 100

- then into the pipe 33. The cool air admitted to the bottom of the casing 25, through the inlet openings 27 will rise up through the hot air pipe 22 where it will be heated by 5 the hot air in the radiator, and after being heated to the maximum point, passes up through the pipe 23 and thence into the conducting pipe 24 which delivers hot air to the various rooms of a building.
- 10 The foregoing description and accompanying drawings have reference to what might be considered to be the approved or preferred form of my invention. I desire it to be understood that I may make such 15 changes in the construction, combination and arrangement of parts, materials, dimensions, et cetera, as may prove expedient and fall within the scope of the invention as claimed hereinafter.
- 20 Having thus fully described my invention what I claim as new and desire to secure by Letters Patent, is:—
1. The combination with a furnace including a fire pot and a grate disposed below 25 the fire pot, of a fuel plate for the furnace including a circular imperforate body disposed axially within the fire pot at the lower end thereof and spaced equi-distantly from the inner surface of the fire pot, and means 30 carried by the plate for engaging the fire pot.
2. The combination with a furnace and grate therefor, a fire pot disposed above the grate, of a fuel plate for the furnace embodying a disk-shaped imperforate body 35 disposed axially in the fire pot adjacent to the lower edge thereof and having its outer edge spaced equi-distantly from the inner surface of the fire pot, the body being disposed above the grate in spaced relation 40 thereto, and adjustable radially extending legs carried by the lower surface of the plate for engaging the fire pot.
3. In a furnace, a fuel plate including a flat imperforate body, a depending flange 45 formed on the lower end of the body and having guide-ways formed therein, outwardly extending slotted arms carried by the lower surface of the body extending through the guide-ways, and bolts carried by the body extending through the slots for holding the arms in an adjusted position on the body, the outer ends of the arms being adapted to engage the fire pot of the furnace. 50
- 55 In testimony whereof I affix my signature in presence of two witnesses:

JOHN T. COLLINS.
